UNITED STATES PATENT OFFICE

GLENVILLE A. COLLINS, OF SAN MARINO, CALIFORNIA

BOILER CONSTRUCTION

Application filed April 23, 1928, Serial No. 272,085. Renewed February 14, 1931.

This invention relates to improvements in boilers.

The general object of this invention is to provide an improved boiler of the water tube type.

A specific object of this invention is to provide a novel boiler wherein a steam drum and a mud drum are connected by a plurality of water circulating tubes and wherein all the circulating tubes are adapted to liberate steam into the steam drum.

A further object of the invention is to provide a boiler wherein a steam drum and a mud drum are arranged at right angles to each other and connected by a plurality of water circulating tubes.

Another object of this invention is to provide a boiler construction wherein a plurality of steam drums are adapted to be connected by water circulating tubes to a single mud drum.

Other objects and the advantages of this invention will be apparent from the following description taken in connection with the accompanying drawings wherein:

Fig. 1 is a section, partly in elevation, showing my improved boiler.

Fig. 2 is a front elevation, partly in section, of the boiler shown in Fig. 1 with a part of the tubes removed, and

Fig. 3 is a diagrammatic view of a boiler made in accordance with my invention showing a plurality of steam drums connected to a single mud drum.

Referring to the drawings by reference characters I have indicated a boiler embodying the features of my invention generally at 10. This boiler comprises a boiler setting 12 having a space 13 for a furnace therein and having a breeching 14 to a smoke stack 15.

The boiler is of the water tube type and includes a steam drum 16 and a mud drum 17. The axis of the steam drum is arranged at right angles to the axis of the mud drum; that is, the longitudinal axis of the steam drum 16 runs from the front to the rear of the boiler and the longitudinal axis of the mud drum 17 runs from side to side of the boiler 10 as clearly shown in the drawings.

The steam and mud drums are connected adjacent the rear of the boiler by a bank of tubes 20 and towards the front of the boiler by a bank of tubes 22.

As clearly shown in the drawings the tubes of the bank 20 curve outwardly from the lower sides of the steam drum at right angles to the longitudinal axis of the steam drum. These tubes also extend straight downward for a distance and then curve inwardly to engage the top sides of the mud drum at right angles to the longitudinal axis of the mud drum. The second mentioned curvature of the tubes 20 is accordingly transverse to the first curvature.

The tubes of the forward bank 22 curve outwardly from the top sides of the mud drum 17 at right angles to the longitudinal axis of the mud drum, then extend upwardly inclined towards the front of the boiler, then curve upwardly and finally curve inwardly to the bottom sides of the steam drum 16. Thus the third curvature is transverse to the first two curvatures of the tubes in the bank 22. The steam drum 16 is shown as provided with a water gauge 24, a steam outlet 25, and may have other accessories as desired.

The boiler may be provided with baffles 26, 27, and 28, which may be arranged in a manner to properly conduct the hot products of combustion to produce the best results. It will be understood that the boiler is adapted for use with various types of heat producing devices whether it is coal, gas, or oil, or other means. The arrangements of the baffles may also be changed to suit various conditions.

The hot gases from the combustion space 13 will first pass between the tubes of the bank 22, then between the tubes of the bank 20, and thence out the stack 15. As the bank 22 is the nearest the combustion chamber the water therein will be heated to a much higher degree than the water in the bank 20, thus the circulation of water will be from the steam drum 16, through the bank 20 to the mud drum 17, and thence through bank 22 to the steam drum. The hot gases also contact with the underside

100

of the steam drum 16 and maintain a high degree of heat therein.

As all the circulating tubes of the boiler open into the steam drum 16, steam disengaged in the bank 20 will be liberated in the steam drum and will not pass through the mud drum 17.

With my improved construction I provide a boiler which is economical to construct owing to the fact that no water drum is used, and which is highly efficient owing to the fact that the hot gases directly from the combustion chamber contact with such a large area of the water circulating elements.

In Fig. 3 I have diagrammatically shown a front view of the arrangements of the drums and tubes of a boiler wherein a plurality of steam drums are connected to a single mud drum. In this boiler steam drums 30 and 31 are connected to a single mud drum 32 by sets of banks of tubes 33 and 34. Each of the sets of tubes 33 and 34 include forward and rearward banks of tubes similar to the banks 20 and 22 of the boiler 10 just described.

It will be understood that in a boiler constructed in accordance with my invention any number of steam drums may be connected to a single mud drum and the steam in the various steam drums may be drawn from each drum separately and used independently or some or all of the steam drums may communicate with a common steam header.

Having thus described my invention, I claim:

In a boiler including a furnace or combustion chamber and a smoke stack at the rear end in the upper portion thereof, a steam drum adjacent the top of the boiler and extending from the front to the rear thereof and a mud drum positioned below said steam drum, the longitudinal axis of said steam drum and the longitudinal axis of said drum being at right angles, a bank of tubes adjacent the rear of said steam drum connecting said steam drum and said mud drum, said tubes being vertical and curved adjacent said steam drum and said mud drum, the curvature of said tubes adjacent said steam drum being arranged at right angles to the curvature of said tubes adjacent said mud drum, another bank of tubes adjacent the front of said steam drum connecting said steam drum and said mud drum, said second bank of tubes being inclined from said mud drum upward and forwardly to said steam drum, said tubes being curved adjacent said steam drum and said mud drum said curved portions being disposed in planes at right angles to each other, a third curve in said second bank of tubes intermediate said first two curvatures, said third curvature being

on a plane at right angles to said curvature adjacent said steam drum and in a direction opposite to the curvature adjacent said steam drum, a baffle plate between said first bank of tubes and said second bank of tubes and extending upwardly from said mud drum, the major portion of the length of the bottom of said steam drum being exposed to hot gases generated in said combustion chamber, a second baffle, said second baffle being vertically arranged between certain of the tubes of said first bank of tubes and extending downwardly from said steam drum and forwardly of said smoke stack.

In testimony whereof, I hereunto affix my signature.

GLENVILLE A. COLLINS.
